UNITED STATES PATENT OFFICE.

ELVY W. BEELER, OF DURANGO, COLORADO.

PAPER TRIMMER.

Application filed September 19, 1921. Serial No. 501,619.

To all whom it may concern:

Be it known that I, ELVY W. BEELER, a citizen of the United States, residing at Durango, in the county of La Plata and State of Colorado, have invented certain new and useful Improvements in Paper Trimmers, of which the following is a specification, reference being had to the accompanying drawings.

10 This invention relates to tools particularly adapted for use by paper-hangers, and has for its object the provision of a novel paper trimmer or cutter designed primarily for cutting off the margins of wall paper.

15 An important and more specific object is the provision of a paper trimmer and cutter designed to be used in conjunction with a straight edge used as a guide, the device including a guide roller of relatively small 20 diameter intended to be drawn along the straight edge and further including a relatively large cutting disk engageable with the paper to be cut, the purpose of the differences between the relative sizes of the 25 roller and disk being to cause faster travel of the cutting edge of the disk for insuring smooth cutting or trimming action.

Another object is the provision of a device 30 of this character which is provided with a handle which is off center so that the device may be reversed so as to be readily capable of use by either a right or left handed operator.

Still another object is the provision of 35 a rotary cutter of this character which is provided with a novel mounting for the roller whereby the roller and cutter disk may be removed bodily from the supporting frame with a minimum amount of trouble.

40 An additional object is the provision of a device of this character which will be simple and inexpensive in manufacture, highly efficient and rapid in use, durable in service and a general improvement in 45 the art.

With the above and other objects and advantages in view, the invention consists in the details of construction to be hereinafter more fully described and claimed, and illustrated in the accompanying drawings, in which:

Figure 1 is an elevation of one side of my device;

Figure 2 is a plan view;

55 Figure 3 is a fragmentary elevation of the opposite side; and

Figure 4 is a cross sectional view taken through the axle of the roller.

Referring more particularly to the drawings, I have shown my device as comprising 60 a U-shaped frame 10 which is formed on its bight portion or back with a socket 11 located nearer to one side of the frame than the other. Engaged within this socket is the reduced end 12 of a handle 13 of suitable length held in place by a rod 14 passing centrally through the handle and having a threaded end 15 screwed into the frame 10. By this connection it will be seen that the handle may be readily removed and replaced in case it should become split or be otherwise rendered unserviceable. The end portion of one arm of the frame is formed with a circular hole 16, while the end of the other arm is formed 65 with a key hole opening or slot 17.

Extending transversely of the frame is an axle bolt 18 which has its headed end 19 formed with a lug and which has its other end threaded and carrying a nut 20. 80 The lug is of such size and shape as to pass through the lateral portion of the key hole slot 17 so that when the axle bolt is inserted in place, rotation will be prevented by the lug while longitudinal movement is prevented by virtue of the engagement of the head 19 upon the edge of the circular portion of the key hole slot 17.

85 The above described axle bolt serves as a bearing for the roller 21 which is provided internally with a rigidly secured bearing sleeve 22 rotating upon the axle bolt 18. Disposed against one end of this roller 21 and secured thereto, as by means of ordinary wood screws 23, is a disk 24 having a 90 beveled cutting edge 25. This disk is naturally formed at its center with a suitable hole for the passage of the bolt 18.

95 In use the device is associated with a suitable table which has its edge provided with the usual straight edge, this table being well known and being of the type commonly employed by paper hangers. The paper to be trimmed or cut is of course laid upon the paper-hanger's table in the usual manner with the undesired margins extending beyond the edge. The operator then grasps the handle of my device and so disposes the tool that the roller 21 will roll upon that portion of the paper overlying the straight edge, 100 with the cutting blade 24 engaging against the outer edge of the straight edge. The 105

device is then pushed along whereupon rotary movement will be imparted to the roller and the disk and the beveled edge of the disk will cooperate with the beveled edge of the 5 straight edge for effecting an efficient shearing action which will cut the paper. Owing to the fact that the disk 24 is of much greater diameter than the roller 21, it will be apparent that the speed of travel of a point 10 on the periphery of the disk will be much greater than the speed of travel of a point on the periphery of the roller and this will cause a much smoother and more rapid cutting action than would occur if these two 15 elements were of substantially the same diameter.

From the foregoing description and a study of the drawings it will be apparent that I have thus provided a simply constructed 20 tool which is well adapted for the use of paper-hangers and in fact every one having occasion to cut or trim wall paper or other similar material in a very efficient manner. It is to be noted that in case of necessity the 25 roller and disk assembly may be removed and that the disk may be easily subsequently removed from its supporting roller in case of any necessity for replacement or the like. It is also to be noted that owing to the fact 30 that the handle structure is located nearer to one side of the supporting frame than the other, the device may be easily used by either a right or left handed operator merely by turning it over, it being desirable that the 35 handle be located closer to the cutting disk than to the opposite side of the tool. This feature of the construction is important in

that it eliminates, in a great measure, the strain applied to the hand during the cutting operation with the usual construction, in which the cutting disk has a tendency to elevate at all times because of the leverage it has upon the handle. With the present construction this leverage is removed and the pressure of the handle to hold the roller in contact with the table is applied practically directly to the cutting disk. The efficiency of the tool is further assisted by providing a heavy roller such as hereinbefore referred to. 40 45 50

While I have shown and described the preferred embodiment of the invention, it is of course to be readily understood that I reserve the right to make such changes in the form, construction and arrangement of parts as will not depart from the spirit of the invention or the scope of the subjoined claim. 55

Having thus described my invention, I claim:

A tool of the character described comprising a U-shaped supporting frame formed at its bight portion to one side of the center thereof with a socket, a handle detachably engaged within said socket, a pivot bolt detachably engaged with and extending transversely across the open end of said frame, a heavy metal roller journaled upon said pivot bolt, a relatively large cutting disk secured to that end of said roller most nearly in alignment with the axis of said handle. 60 65 70

In testimony whereof I hereunto affix my signature.

ELVY W. BEELER.
